UNITED STATES PATENT OFFICE.

JOHN F. CARPMILL, OF NEW BRITAIN, CONNECTICUT, ASSIGNOR TO THE NORTH & JUDD MANUFACTURING COMPANY, OF NEW BRITAIN, CONNECTICUT, A CORPORATION OF CONNECTICUT.

BIT.

1,267,972.

Specification of Letters Patent. Patented May 28, 1918.

Application filed July 31, 1917. Serial No. 183,699.

To all whom it may concern:

Be it known that I, JOHN F. CARPMILL, a citizen of the United States, residing at New Britain, in the county of Hartford and State 5 of Connecticut, have invented certain new and useful Improvements in Bits, of which the following is a specification.

This invention relates to bits. The main object of the invention is to provide an 10 article of this character which can be inexpensively, readily and quickly made and which possesses the requisite strength.

In the drawings accompanying and forming part of the present specification I have 15 shown in detail one of the several convenient forms of embodiment of the invention, which to enable those skilled in the art to practice the same will be set forth fully in the following description. I do not restrict 20 myself to this exact disclosure; I may depart therefrom in several respects within the scope of the invention defined by the claim following said description.

Referring to said drawings:

25 Figure 1 is a front elevation of a bit involving the invention.

Fig. 2 is a side elevation of said bit, and

Fig. 3 is a cross section on the line 3—3 of Fig. 1.

30 Like characters refer to like parts throughout the several views.

The bit involves in its make-up cheeks such as those denoted in a general way by 2, and a mouth-piece or bit proper as 3. One 35 of the motives I have in view is the construction of the article in a very inexpensive manner. This result I can achieve while maintaining the requisite strength or rigidity. In the form of the article selected for illustration herein, it consists merely of two 40 parts or pieces, and while these can be of any suitable material, I prefer as a matter of advantage that they be of wire of the necessary grade and preferably circular, or

45 virtually so, in cross section. These two members are denoted by 4 and 5 respectively and are practically of duplicate construction, although they face oppositely. Each has a transverse portion 6 and two terminal portions 7 and 8, the terminal portion 7 of

the part or element 4 coöperating with the terminal portion 8 of the part 5 and the other terminal portions 7 and 8 also coöperating with each other to constitute as will hereinafter more particularly appear, the 55 cheeks 2. I might observe at this point that the portions 7 are provided at their ends with eyes 9 which are in alinement transversely and which act as rings to receive the cheeks of a bridle. The portions 8 also terminate in eyes 10 which act as rein rings or to receive the driving reins of said bridle, which likewise are in transverse alinement. The respective eyes can be formed either before or after the sections 4 and 5 are connected with each other. As I say the said sections 4 and 5 initially are of zigzag form, the terminal portions 7 and 8 of the respective members extending oppositely from the ends of the transverse or connecting member 6. These two transverse or connecting members 6 are intercoiled, intertwined or intertwined as indicated by 11, so as to present a mouth-piece or bit proper as 3 to which I have already referred. The inter- 75 coiling of the two portions 6 is one way of uniting them in a substantial and solid fashion and does not in any manner affect their efficiency. Just short of the ends of the coiled portion 11 the parts 6 diverge out- 80 wardly and are then deflected laterally so that the parts 7 and 8 respectively are brought into coincidence or line with each other.

While the mouth-piece of the bit com- 85 prises a plurality of intercoiled portions which is a desirable construction, this might not always be necessary. The invention as to one of its features comprises a bit which has merely two parts or main parts and 90 which collectively present the mouthpiece and the cheeks. As will be understood in any event, however, the invention involves certain broad principles.

What I claim is:

95 A bit comprising two zigzag elements, the transverse portions of the elements being intercoiled to present the mouth-piece of the bit, two end portions coöperating to present one cheek of the bit and the other two end 100

portions coöoperating to present the other cheek of the bit, each of the end portions terminating in an eye, two of the eyes being adapted to receive bridle cheeks, and the 5 other two being adapted to receive driving reins, the end portions which coöperate as bit cheeks being approximately coaxial.

In testimony whereof I affix my signature in the presence of two witnesses.

JOHN F. CARPMILL.

Witnesses:

GEORGE W. TROOP,

JOHN J. CREAN.
